UNITED STATES PATENT OFFICE.

CLINTON V. WOOLMAN, OF TACOMA, WASHINGTON.

FIREPLACE SUPERHEATER.

Application filed March 30, 1928. Serial No. 266,031.

This invention relates to superheaters adapted for use within fire places, open hearths etc., embodying among other characteristics a baffle plate adapted to deflect 5 heat therefrom and within the room which is ordinarily drawn up through the chimney flue.

Another object of the invention comprehends a damper plate operable in conjunction 10 with the baffle plate to open and close the flue in the superheater and to provide an extension for the baffle plate to deflect more of the heat when the fire burns low.

A further object of the invention contemplates a smoke chamber provided within the 15 upper portion of the superheater and extended at right angles from the heater per se, whereby the smoke when drawn against the top of the superheater will deflect the heat 20 therein downwardly against the damper and baffle plate through the heating compartment and into the room.

More specifically stated, the damper plate is provided with control members extended 25 through a face plate for the heater.

With the above and other objects in view, the invention further consists of the following novel features and details of construction, to be hereinafter more fully described, 30 illustrated in the accompanying drawings and pointed out in the appended claim.

In the drawings:—

Figure 1 is a side elevation of the invention as applied within a fire place.

Figure 2 is a front elevation of the invention with the cover plate and damper control removed.

Figure 3 is a sectional view taken on line 3—3 of Figure 2.

Figure 4 is a sectional view taken on line 4—4 of Figure 3.

Figure 5 is a bottom plan view of the superheater per se.

Referring to the drawings in detail, where- 45 in like characters of reference denote corre- 10 sponding parts, the reference character 10 indicates an elongated box like housing pre- 15 ferably composed of castiron or sheet metal and which is provided with a cover plate 11 20 upon the outer portion thereof, the face plate 25 being of any ornamental design.

A baffle plate 12, horizontally disposed 30 upon the rear wall 13 of the housing 10 and 35 extending the entire length of the housing 40 therein, is retained in the position shown 45 against warping incident to contraction and

expansion through the instrumentality of a brace member 14.

Fins 15, inwardly projected from the inner- 60 sides of end walls for the housing, are dis- 65 posed in spaced relation to and above the baffle plate 12. A damper plate 16 slidably mounted upon the upper side of the baffle plate 12 is retained in position by the fins 15.

Ears 17, upstanding from the forward side 65 edge of the damper plate 16 are apertured and tapped to accommodate the innermost threaded ends of rod members 18 having pivotal connection, as indicated at 19 with damper pulls or levers 20. The latter are 70 adapted to depend in the positions shown in Figure 1 of the drawings when the damper has been fully closed, whereas the levers or pulls will occupy horizontal positions when the damper is open as substantiated in Figure 75 3 of the drawings.

It will thus be noted that compartments 21 and 22 are defined within the housing 10. The compartment 21, by reason of the fact that the same is the lowermost of the compartments, will initially receive the heat and smoke from the fire within the fire place. Said compartment having the upper wall 80 thereof composed of the baffle plate 12 and damper plate 16 will obviously deflect a great 85 quantity of heat downwardly through the compartment and within the room. Such heat would be ordinarily lost and drawn up through the chimney flue. The compartment 22 is in the nature of a combination heat and 90 smoke collecting chamber, which will absorb the heat and radiate the same through the cover plate 11 rather than allow the same to pass up through the chimney inasmuch as the draft opening, controlled by the damper 95 plate 16, is located immediately behind the cover plate 11.

A compartment 23 having communication with the rear wall 13 of the compartment is 100 adapted to establish means of communication between the compartment 22 and a chimney flue 24. The lower wall of the compartment 23 is adapted to repose upon the upper ledge of an auxiliary wall 25, preferably composed of fire brick or other fire resisting material, 105 whereby the entire superheater device may lie flush with the face of the fire place and to effectively radiate heat therefrom within the room.

The invention is susceptible of various 110 changes in its form, proportions and minor details of construction, and the right is herein

reserved to make such changes as properly fall within the scope of the appended claim.

Having described the invention, what is claimed is:—

- 5 The combination with a mantel fireplace having a rear wall and an opening through said wall to provide communication with the fireplace flue, of a heater comprising a housing positioned within the fireplace with the front wall of the housing flush with the front wall of said fireplace, said housing having an opening in its bottom adjacent its front wall for the entrance of products of combustion, a partition extending horizontally within 10 the housing from the rear wall thereof and having its front edge spaced from the front wall of the housing, said partition providing

a baffle and dividing the housing into a lower compartment and an upper compartment, a damper to control the passage of the products of combustion from the lower to the upper compartment, and a relatively narrow rear hollow extension projecting from the rear of and communicating with the upper compartment and having its top and bottom walls closely engaging the top and bottom walls of the opening in the rear wall of the fireplace, and the rear wall of the lower compartment of the housing engaging the front of said rear wall of said fireplace, and said rear extension providing a restricted passage between the upper compartment and the fireplace flue.

In testimony whereof I affix my signature.

CLINTON V. WOOLMAN.
